T. JACKSON.
MARINE ENGINE GOVERNOR.
APPLICATION FILED JUNE 11, 1919.

1,413,586.

Patented Apr. 25, 1922.

INVENTOR:
Thomas Jackson
By Mr. Wallace White
ATTY.

UNITED STATES PATENT OFFICE.

THOMAS JACKSON, OF LEWISHAM, LONDON, ENGLAND, ASSIGNOR TO ALLAN RAMSAY,
OF FOLKESTONE, ENGLAND.

MARINE-ENGINE GOVERNOR.

1,413,586.

Specification of Letters Patent. Patented Apr. 25, 1922.

Application filed June 11, 1919. Serial No. 303,467.

(GRANTED UNDER THE PROVISIONS OF THE ACT OF MARCH 3, 1921, 41 STAT. L., 1313.)

To all whom it may concern:

Be it known that THOMAS JACKSON, subject of the King of Great Britain and Ireland, residing at 27 Mount Pleasant Road, Lewisham, London, S. E., England, has invented new and useful Improvements in Marine-Engine Governors, (for which I have filed application in Great Britain, November 17, 1917, Patent No. 120,768,) of which the following is a specification.

This invention relates to marine engine governors in which a power device operating the throttle valve is controlled by an inertia governor driven by the engine itself, or by an anticipatory governor of the tilttable gravity controlled type having a mobile body and adjustable relative to the ship and controlled by the angular movement of the ship in a vertical plane while traveling through the water, or by both of said governors.

This invention refers more particularly to the class of governing device described in the specification of United States Letters Patent No. 919713, issued 27th. April 1909, but it must be understood that it is applicable to any similar type of governor in which a power device, operated by fluid pressure, is adapted to operate the throttle valve or other regulating device of the engine.

In order that the invention may be the better understood I will now proceed to describe the same in relation to the accompanying drawing, reference being had to the letters and figures marked thereon. Like letters refer to like parts in the various figures, in which:-

Fig. 1 is a general view of the arrangement of an inertia governor, an anticipatory governor of the tilttable gravity controlled type, a control valve and a power device for operating the throttle valve with a relay device arranged in connection with the control valve.

Fig. 2 is a sectional detail view of cylinder 45 of the relay device, the piston with its rod being shown in full.

Fig. 3 is a view of the stem of the control valve with an adjustable locking collar.

Referring to the drawings, *a* designates an inertia governor which is operated from the marine or other engine, *b* an anticipatory governor comprising a tilttable member, *c* a valve device for controlling the reverse operations of the power device *d* to open

and close the steam throttle of the engine, 55 and *e* a relay device which is connected with and operates the valve in the valve device *c*. *i* designates a pipe connection in which a vacuum is maintained, it being connected, for example, with the condenser system of 60 the marine or other engine, so that there will be present in the pipe *i* the same vacuum as is maintained in the condenser. The casing *c* of the valve device is also connected with the pipe *i* as here shown through 65 the pipe *i*¹ and the interior of the governor *b* is also connected with the pipe *i* as here shown through the pipes *i*² and *i*¹. The relay device *e* is also connected with the pipe *i* as here shown through the pipe *i*³, governor 70 device *b*, and pipes *i*² and *i*¹, and it is also connected with the pipe *i*, by a pipe *i*⁴ in which a valve is located and which valve is operated by the inertia governor *a*.

The anticipatory governor *b* may preferably be of the construction shown and described in British Patent No. 120767. The governor *b* is adjusted so that the tilttable member thereof will have a position to close the pipe *i*³, but when the movement of the ship in a vertical plane is more than for which the movement of the governor is adjusted, it will open the pipe, and permit the vacuum to be effective in the relay device *e*, 75 under the piston *g*, so that atmospheric pressure acting through the openings *r* in the top plate *s* of the cylinder *f* will move the piston *g* downward and thus move the valve in the valve device *c* so that the atmospheric pressure will be cut off from below 80 the piston in the power device *d* and the vacuum applied to that side, and at the same time applying atmospheric pressure to the upper side of the piston of the power device and thus move it to close the throttle. When, 85 however, the tilttable member is returned to its adjusted position by the mobile member, the vacuum is cut off from the under side of the piston *g* whereupon the spring *j* will return the piston *g* to the position shown (Fig. 90 100 105 110 115 120 125 130 135 140 145 150 155 160 165 170 175 180 185 190 195 200 205 210 215 220 225 230 235 240 245 250 255 260 265 270 275 280 285 290 9635 9640 9645 9650 9655 9660 9665 9670 9675 9680 9685 9690 9695 9700 9705 9710 9715 9720 9725 9730 9735 9740 9745 9750 9755 9760 9765 9770 9775 9780 9785 9790 9795 9800 9805

sectional area which is regulated by the screw *k*.

The cylinder *f* is fitted with an adjustable valve *k* by which a certain amount of leak to atmosphere or bye-pass from the bottom to the top of the piston *g* can be effected so that in the event of the operation of the inertia governor *a*, or the anticipatory governor *b*, being of merely momentary effect, the relay device *e* is not completely operated and the throttle valve position is not interfered with. The inertia governor *a* shown in the drawing comprises an arm carrying a weight adapted to be oscillated about an axis through the medium of a lever and connecting rod which is actuated by a reciprocating part of the engine; the relation of the arm carrying the weight to the lever being spring controlled.

These elements are so arranged that when the arm carrying the weight is oscillated at a normal speed its movements do not differ from those of the lever, but when an increase beyond the predetermined speed occurs then the arm carrying the weight moves relatively to the lever thereby putting the relay device *e* in communication with the vacuum.

Quite apart from the saving of wear and tear and the useless expenditure of energy, the objectionable feature of "hunting" between the device governing the operation of the engine and the operation of the engine itself, is entirely avoided.

It will be recognized that only one relay device *e* need be used when both an inertia and an anticipatory governor are connected, as shown in the drawing, as such relay device is common to the two.

It has been suggested in the past that on excessive speed being attained by the engine, the control valve *c* of the power device should be locked when such extreme conditions have obtained, necessitating the unlocking of the locking device by hand. In order to make this provision more useful the locking device is made adjustable so that the locking operation can be adjusted to take place at any predetermined speed desired. This is effected by screwing the engaging collar *l* on the upper end of the spindle *m* of the control valve *c* and when adjusted by fixing it rigidly in position by

a lock nut *n* so as to engage the spring detent *o* at any given position.

55

What I claim is:—

1. In a governing apparatus for marine engines, comprising a power device operated in reverse directions by atmospheric pressure to open and close a throttle; a valve device for controlling the operation of the power device; a relay device for controlling the operation of the valve device; said device being operated in one direction by atmospheric pressure; means for maintaining a vacuum; and a governor device for applying the vacuum to the relay device whereby it may be operated by atmospheric pressure to move the said valve device.

2. Governing apparatus for marine engines comprising a power device for the throttle which is operated by atmospheric pressure in its control of the throttle; means for maintaining a vacuum; a valve device for controlling the application of the vacuum to either side of the power device; a second power device for operating the valve device and also operated in one direction by atmospheric pressure; and a device for controlling the application of the vacuum to the second power device, said device comprising a tiltable member movable in accordance with the pitch of a ship above a predetermined amount.

3. Governing apparatus for marine engines comprising a power device for the throttle which is operated by atmospheric pressure in its control of the throttle; means for maintaining a vacuum; a valve device for controlling the application of the vacuum to either side of the power device; a second power device for operating the valve device and also operated in one direction by atmospheric pressure; and an inertia device operated from the engine for controlling the application of the vacuum to the second power device when the engine exceeds a predetermined speed.

In testimony whereof I have signed my name to this specification in the presence of two subscribing witnesses.

THOMAS JACKSON.
